UNITED STATES PATENT OFFICE.

EDWARD D. MEIER, OF ST. LOUIS, MISSOURI.

STEAM-GENERATOR AND HOT-WATER HEATER.

SPECIFICATION forming part of Letters Patent No. 595,641, dated December 14, 1897.

Application filed July 15, 1896. Serial No. 599,209. (No model.)

To all whom it may concern:

Be it known that I, EDWARD D. MEIER, a citizen of the United States, residing at the city of St. Louis, State of Missouri, have invented a certain new and useful Improvement 5 in Steam-Generators and Water-Heaters, of which the following is a full, clear, and exact description, reference being had to the accompanying drawings, forming a part of this 10 specification, in which—

Figure 1 is a longitudinal sectional view through a steam-generator and water-heater embodying my invention. Fig. 2 is a front elevational view, with the front plate of the 15 water-leg removed, showing a slightly different form. Fig. 3 is a longitudinal sectional view on the line 3 3, Fig. 2. Fig. 4 is a front elevational view, the front plate of the water-leg being removed, showing a slightly different 20 form; and Fig. 5 is a sectional view on line 5 5, Fig. 4.

This invention relates to a new and useful improvement in steam-generators and water-heaters of that class known as the "Heine" 25 type, such as illustrated in United States Letters Patent No. 304,195, granted to Hermann Heine August 26, 1884.

The object of my present invention is to so construct the front and rear water-legs that 30 the circulating water therebetween and the drum will be unobstructed—that is, the throat area of the water-legs where they connect to the drum will be substantially the same, more or less, as the end area of the 35 drum.

With this object in view the invention consists in so constructing the front and rear water-legs that the drum will open thereinto with its full end area. Incidental to this the 40 outer plates of these water-legs are so constructed as to resist the pressure due to this end area. Another feature of the invention resides in arranging strengthening rings around these water-legs, as will hereinafter 45 appear.

Other features of the invention reside in the construction, arrangement, and combination of the several parts, all as will herein-after be more fully described, and afterward 50 pointed out in the claims.

In the drawings, A indicates the drum, B the mud-drum, C the steam-dome, and D

the water-tubes, all such parts being of well-known construction.

The front and rear water-legs being substantially the same I will describe but one of them—the front.

E indicates the back or inner plate of the water-leg, which is flanged forwardly at its side edges to meet the front plate, thus forming a water-space between them. The upper part of this back plate is formed with an opening and flanged, as at F, to which flange is secured the front end of drum A. G indicates the front plate of the front water-leg, whose outer or side edges are flanged rearwardly, said flanges meeting the corresponding flanges of said plate E to form the water-space between them. These flanges are secured together by a strap H.

I indicates suitable stay-bolts, which are arranged between the plates E and G and whose purposes and location are well understood. These stay-bolts extend practically over the entire area of the front and back 75 plates to brace them at all points.

As shown in Figs. 1 and 5, the front plates are bulged outwardly, as at J, in line with the drum in order that the plate may be strengthened at this point, because it is impossible to attach stay-bolts to the inner plates E. In Fig. 3 this front plate is shown flat—that is, the bulge J referred to is not present. In order to further strengthen these plates around the tubes D and hand-holes, I prefer 85 to flange the front and back plates to the rear, as shown in Fig. 3. In some instances it may be desirable to strengthen these plates around the drum A and bulge J, and in order to do this I arrange thereon rings K, through which 90 the circular series of stay-bolts around said parts pass.

Having thus described my invention, what I claim, and desire to secure by Letters Patent of the United States, is—

1. The combination with front and back water-legs whose upper ends are formed with an opening having a flanged edge, of a drum fitting in said opening and secured to the flanged edge, and water-tubes between the lower ends of said legs; substantially as described.

2. The combination with a water-leg whose upper end is formed with an opening in one

side, said opening having a flanged edge, of a drum whose end fits in said opening and is secured to said flanged edge, and a bulge in the other side or wall of the water-leg, said 5 bulge being in line with the drum; substantially as described.

3. The combination with the front and back water-legs which are connected at their lower ends by water-tubes, and a drum connecting 10 the upper ends of the water-legs and opening thereinto with its full end area, said legs being bulged in line with the drum to strengthen the water-legs; substantially as described.

4. The combination with the water-legs, of 15 water-tubes connecting the lower ends of the same, a drum connecting the upper ends of the same, said water-legs being bulged in line with the drum to give them strength, rings around said bulged portion and drum-flange, 20 and stay-bolts; substantially as described.

5. The combination with front and back water-legs, the upper ends of whose inner plates are formed with openings having flanged edges, of a drum fitting in said open- 25

ings and secured to the flanged edges thereof, 30 the lower ends of said inner plates being formed with tube-openings having flanged edges, and water-tubes secured in said flanged tube-openings, substantially as described.

6. The combination with the outer plate of 35 a water-leg which is formed with series of inwardly-flanged hand-holes, the flanges of which afford raised seats for the hand-hole plates, of an inner plate formed with outwardly-flanged holes to afford extended bearings for the water-tubes, water-tubes in the outwardly-flanged openings of the inner plate, and stay-bolts connecting said outer and inner water-leg plates; substantially as described. 40

In testimony whereof I hereunto affix my signature, in presence of two witnesses, this 27th day of June, 1896.

EDWARD D. MEIER.
